SPIRAL STITCH MECHANISM FOR
SEWING MACHINES

Anthony Guide, Somerville, N. J.

Application May 27, 1952, Serial No. 290,191

9 Claims. (Cl. 112—2)

1

The present invention relates to sewing machines and more particularly to a method and means for producing a spiral seam on a work-piece. In its more specific aspects the invention undertakes to render available an efficient apparatus for producing a spiralling seam or line of stitches on cup-shaped brassière elements or other shaped forms of work as well as on flat work.

Another objective of the invention is the construction of a spiral stitching mechanism, preferably but not necessarily, in the form of an attachment that may be conveniently applied to existing sewing machines and to cooperate with the conventional stitching mechanism to cause the resulting seam to be formed in a spiral with one or more spaced convolutions. The invention further aims to provide a mechanism for producing a spiral seam on relatively large or relatively small work pieces and one that is capable of convenient adjustment so that the spacing of the convolutions of the spiral may be altered to suit the nature of the work, the needs, or one's preferences as to the number of convolutions to be produced on a given piece.

In some respects the present invention and application is a continuation in part of my earlier filed application, Serial No. 268,954, filed January 30, 1952, but which, however, is a distinct improvement over the earlier structure, not only in simplicity in design and operation, but in an improved relation and coaction of cooperating elements by means of which the efficiency, versatility, and range of the spiral seam producing mechanism is greatly increased.

The present invention proposes a simple mechanism that may be a built-in part of a sewing machine or which may be constructed as an attachment. Essentially the invention comprises a movable work guide that carries a center on and about which a preformed brassière cup or similar workpiece is revolvably fixed, and a transmission train between the main drive of the machine and the movable work center. The transmission train includes a cam and lever system and preferably a change-speed means whereby the rate of movement of the work center relative to the speed of the machine may be varied at will. The parts are so constructed and arranged that the stitching is done on the inside of the brassière cup, that is, the cup is placed on the work-guide center and held at its polar axis by a piercing point a short distance laterally offset from the needle of the machine. One side

5 of the cup is caused to under-lie the presser foot and the portions of the cup immediately ahead and behind the presser foot curve upwardly, away from the plane of the table. The presser foot thus engages the inside of the cup and the feeder jaw, the outside of the cup. The generally spherical contour of the cup makes, accordingly, a localized engagement with the feeder teeth but never-the-less an engagement adequate to feed the material. As the stitching progresses, the 10 cup being transfixed by the pin at its polar axis, is free to revolve and does revolve about that axis. Simultaneously the cam and lever system is caused to operate slowly, and through the means 15 to be described, effects a shifting of the polar axis of the work laterally in timed relation with the stitching and in proportion to the ever changing size of the spiral to be formed. The present spiraling device is especially useful in connection 20 with sewing machines equipped with devices for changing the length of the stitch, for when the length of the stitch is increased, the spacing of the convolutions of the spiral become closer, because the machine speed and cam speed remain 25 constant, but the number of stitches per inch of work travel decreases whereby convolutions of the spiral become more closely spaced. However, to vary the spacing of the spiral convolutions, the ratio between stitching-speed and cam-speed 30 must change, and this is readily effected by speed varying means provided in the drive train to the work carrying center. The present invention, therefore, comprehends a machine driven 35 mechanism for automatically producing spiral seams on hemispherical work and with which the size of the stitch, as well as the spacing of the convolutions of the spiral, may be independently varied to suit particular requirements.

Other objects and advantages will be in part 40 indicated in the following description and in part rendered apparent therefrom in connection with the annexed drawings.

To enable others skilled in the art so fully to apprehend the underlying features hereof that 45 they may embody the same in the various ways contemplated by this invention, drawings depicting a preferred typical construction have been annexed as a part of this disclosure and, in such drawings, like characters of reference denote corresponding parts throughout all the views, of 50 which:

Figure 1 of the drawings is a plan view of a spiral stitching machine embodying this invention, parts of the conventional sewing machine 55 being omitted.

Figure 2 is a side elevational view of Figure 1. Figures 3, 4 and 5 are respectively plan and sectional views of portions of the cup centering and stitch feed means.

Figures 6 and 7 are representative views of a spirally stitched brassière cup.

Referring more particularly to Figure 1, the invention disclosed has been illustrated in the form of an attachment capable of ready application to a conventional sewing machine whereby the latter, without serious alteration or delay may be quickly converted to a machine for spiral stitching of hollow work. The principle of this invention may of course be embodied in a custom built machine, as will be understood. In the form illustrated, however, the main elements of the invention are supported upon a relatively thin plate herein illustrated as three plates 10, 11, and 12 that are placed about the bedplate 13 of the sewing machine 14 and suitably secured to the tabletop 15. In the instant embodiment the upper surfaces of the plates lie substantially in the plane of the upper surface of the bedplate 13 and form in effect, a continuation of the working surface thereof.

The sewing machine indicated at 14 is of conventional design having the customary upper and lower thread guides, needle carrier, presser foot and feed jaws indicated at 16 and 17 respectively in Figures 3 and 4. In accordance with this invention the presser foot 16 and the feed jaws 17 are especially constructed so that they are effective only at one side of the needle 18 whereby the forward feed of the material is caused to occur primarily at that one side, preferably the wheel head side of the needle 18. A work supporting guide 19 which holds the work centering means 20, is positioned at the other side of the needle. The work supporting guide 19 comprises in this instance a relatively long lever member that is pivoted at 21 to the plate 12 at the operator's side of the machine and carries adjacent the sewing needle a removable work centering piece 22. The centering piece 22 is provided with an opening at 23 adapted to receive a work piercing point 24. The point 24 is carried at the free end of an over-arm 25 that in turn is mounted to a block or weight 26 in a support 27. Support 27 is mounted upon and is carried by an extension 28 of lever 19 so that the overarm 25 and centering means 20 and 23 may move laterally as a unit. Lever 19, as indicated in Figure 1, has its pivotal axis substantially aligned with the normal line of feed of the sewing machine so that as the work guide is moved angularly about that point, the work centering means 20 and 23 move in an arc in a direction substantially normal to the direction of feed produced by the modified presser foot 16 and feed jaws 17 of the machine.

This invention proposes an efficient means for actuating and controlling the rate of lateral movement of the work center relative to the rate of forward feed whereby it becomes possible automatically to form a spiralling seam on the work piece. As illustrated more clearly in Fig. 1, the work-guide lever 19 is fashioned with a second extension 29 whose edge 30 is curved and forms a cam-track that is normally engaged by a cam-follower roller 31. The follower 31 is carried by and at one end of an arm 32 that is supported upon and pivots about a pivot shaft 33. At the rear side of the pivot 33, a curved extension 34 is provided, which in this embodiment may be an integral part of arm 32, and which

has its inner edge 35 especially contoured to function as a cam-track for a main actuating follower 36. The follower roll 36 is mounted upon a lever 37 that is pivotally supported for movement about an axis 38. Pivotal axis 38, 33, and 21 preferably are substantially in alignment, as illustrated, and the needle 18 stitches approximately on that line.

With reference to the position of the parts shown in Figure 1, it will be seen that when the main actuator roller 36 moves counter-clockwise about its pivot 38, it engages the cam track 35 of lever 34 and moves the latter clockwise about pivot 33 and its other arm 32 and follower 31 is caused to engage cam track 30 and move lever 29, 19 counter-clockwise about its pivot 38. The combined movements of the two cams and followers thereby causing the work supporting elements 20, 22, and 23 to shift laterally. It will be seen further that by giving the cam track 30 a curved formation, the work supporting center 22 and 23 may be caused to respond at a progressively decelerating rate, and by curving the track 30 the effectiveness of the movement imparted by levers 34 and 32 to the work support remains substantially constant. Compensation for the constantly varying angular relation of lever 19, 29 and its actuator 32 is thus automatically made and consequently relatively large spirals may be formed.

The main actuating follower 36 and its lever 37 are propelled in this embodiment by a unidirectional ratchet gear 39 and a pawl element 40. The pawl 40 is pivoted at 41 on the lever 37 and is tensioned by a pull-spring 42 normally into engagement with the teeth on the gear 39. The gear 39 is secured to a vertical shaft 43 which is an output shaft of a speed reducing unit R. The speed reducer may be suitably secured to the under-side of the plate 10, and comprises essentially a main housing 45 in which are journaled two pairs of worm and gear elements 46, 47, 48 and 49 arranged in series. The driven gear 49 is secured to the output shaft 43, and the driver worm 46 is secured to an input shaft 50. Shaft 50 extends beyond the housing 45 and is provided with an extension 50a on which a set of cone pulleys 51 may be mounted. In this embodiment, a sleeve-like support 52 is provided for the drive shaft extension 50a.

Power for operating the drive shaft 50a may be taken from the wheel head 14a of the machine or from the main motor of the machine, here indicated as the shaft 53, by means of a belt 54, and, if desired, a second set of cone pulleys 55. The belt 56 and pulley 57 are connected to drive the sewing machine as will be understood, and when this driving relation obtains its will be seen that the transmission for effecting lateral feed of the work piece is driven in synchronism with the transmission that drives the stitch forming mechanism of the sewing machine. Assuming that the speed reduction afforded by the reducer R is on the order of 2500:1, and that a given step in the pulley drive 51, 54 and 55 provides another reduction of say 4:1, it will be seen that the rotary movement imparted to ratchet gear 39 for each stitch cycle is indeed very small, and this small movement, transmitted through the system of cam levers to the work support center 20, 22, and 23 effects an almost imperceptible lateral movement of the work. However, if the machine is set for making say 12 stitches per inch, and if a given convolution of the spiral is one inch long, the

machine will have made 12 stitching cycles for that convolution and the work piece will have shifted laterally the spacing of one convolution. Accordingly, therefore, should the length of stitch be increased to ten per inch, there will have been ten stitching cycles for that convolution and the lateral shift of the work will be slightly less than before. Therefore, by suitably selecting the length of stitch, the spacing of the convolutions in the spiral may be changed to suit. Also, by increasing or decreasing the rate of speed of the lateral feed transmission relative to the rate of speed of the forward feed transmission, the spacing of the convolutions of the spiral may be varied. It has been found that a four step pulley 51 provides ample variation to cover a wide range of work, and which in combination with the variation produced by changing stitch length as explained above, an almost infinite number of spiral spacings may be produced.

As above explained, the drive pawl 40 normally engages the teeth of the gear 39 but is arranged to be released therefrom at the end of the stitching operation by means of a release shoe 60. The shoe may be formed with a curved edge 61 that lies normally within or below the point of engagement therewith of a roller 40a carried by the pawl 40. The shoe 60 is pivoted as at 62, and at a point 63, beyond its curved track portion 61, it is connected to a pull-lever 64. Lever 64 extends toward the front of the machine and is provided with a handle 65. Adjustable stop collars 66 are provided on the rod at opposite sides of a fixed abutment 67 to limit the movement of the release shoe. A pull spring 68 connected with the shoe normally constrains the shoe out of engagement with the pawl roller 40a. In the position illustrated in Figure 1, the release shoe is retracted and the pawl is in the driving engagement with gear 39. However, when the handle 65 is pulled out, the shoe advances, engages the follower 40a and releases the pawl from the gear, and lateral feed of the work ceases. When the pawl is released from the gear a spring 70, connected to cam lever 32, 34 and a stationary collar 71, retracts the cam lever to starting position as determined by an adjustable stop 72 that is provided. If desired pawl lever 37 may be reset by a pulley and weight mechanism indicated at 73 to avoid using too strong a spring at 70. In either case, however, when the pawl is released, by the release shoe 60, the pawl roller 40a rides back on the track 61 to its starting point as may be determined by a stop pin 74. Stopping of the lateral feed automatically at a selected point may be obtained by the provision of an enlargement of the shoe track as indicated at 61a. As the pawl lever 37 moves counter-clockwise under the impulse of the ratchet gear 39 the pawl roller 40a, will at the selected point, engage the lobe 61a and be cammed out of the teeth of ratchet gear, thus suspending the drive.

In the styling of brassière elements, one may with the present invention commence forming the spiral seam with the first few stitches or cause the spiral to run out of a small circle at the polar axis of the cup. If the former is desired, the stop 74 is adjusted to the position illustrated in Figure 1 wherein the pawl 37 is retracted to a position such that the roller 36 engages the beginning of the cam track 35 of lever 34. As soon as the stitching starts, therefore, the pawl lever roller 36 begins to actuate lever 34 about its pivot 32. These movements 75

are transmitted lever 39, through the follower 31 and cam track 30, and the work shifts laterally. When, however, a preliminary circle is desired, the stop 74 may be adjusted back from the position shown in Figure 1 so that the follower 36 is spaced from and starts a little distance away from cam track 35. Under such conditions the initial movement of the ratchet gear and pawl lever has no effect on the cam lever 34 until the gap is taken up. The adjustment of the stop 74 is to be such that the stitching mechanism will have revolved the work about the center 23 one revolution during which time the pawl lever follower 36 will have traversed the gap and is in position to start actuating the lever 34. It will be observed that by properly correlating the adjustments made to the two stops 72 and 74, the work to be spirally sewn may be started with a preliminary circular seam of any desired size.

To operate the attachment, the operator will swing the work supporting lever 18 to the left (from the position shown in Figure 1) and lift up the over-arm 24. As indicated in Figure 1, the plate 11 may be formed with a curved recess 11a, which receives the projecting portion of the work pivoting needle 23. After centering the work blank upon the center 20, the over-arm is lowered so as to pierce the work with its needle 23. The assembly is then moved toward the stitching needle, as the outer edge of the work is guided under the presser foot, until the center of the work occupies a position close to the stitching needle 18, or such distance therefrom as determined by the adjustable stop 72 which locates the follower 31 against which the work supporting lever stops. The presser foot is then lowered on the work, and after replacing a shield 80, the sewing machine may be started. By virtue of the forward feed of the material being effected and confined to that side of the stitching needle 18 opposite the center about which the work revolves, renders the operation of revolving the work as an incident of the forward feed motion, easy of accomplishment, even on fairly delicate materials.

The shield 80 is provided to aid in holding hemispherical work open and to facilitate the feed thereof under the presser foot 16. The shield 80 may be supported at the end of a looped rod 81 that is carried by a weighted pivot block 82, the latter being pivoted as at 83 to a bracket carried on the plate 12. In removing and replacing work this shield may be lifted out of the way, as will be understood.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. In combination with a sewing machine having stitch forming means including a needle, a presser foot, and feed means adapted normally to feed the work in a forward direction, means to imparting a feed movement to the work in

a direction transverse the direction of forward feed comprising a laterally movable work support, a transmission for actuating said support including a rotatable member, means for driving said rotatable member in synchronism with the operation of the stitch forming means of the machine, normally operative connections between said rotatable member and the said work support, said connections including a pivoted lever having a cam surface engaged by said rotatable member and operatively responsive to the movement of said rotatable member, the said forward feed means of the sewing machine being operative at one side only of the needle of the machine, and means for mounting the work to said work support for angular movement about an axis offset from the needle axis and at the side of the latter opposite the said forward feed means.

2. An apparatus for use with a sewing machine having stitch forming means including a needle, a presser foot, and feed means adapted normally to feed the work in a forward direction, comprising a laterally movable work support, a feed transmission for actuating said support in a direction transverse the direction of the normal forward feed, including a rotatable member, means for driving said rotatable member, normally operative connections between said rotatable member and the said movable work support including a pivoted first lever normally connected to the said rotatable member to revolve therewith, a pivoted second lever adapted to be actuated by and in response to actuation of said first lever, means for transmitting the motion of said second lever to said work support, including a follower element carried by the said second lever, said work support having a curved portion positioned so as to be engaged by said follower element, and means for rendering the connection of said first lever to said rotatable member selectively effective and ineffective.

3. In combination with a sewing machine having stitch forming means including a needle, a presser foot, and means operative at one side of the needle only to feed the work in a forward direction, a means for imparting a feed movement to the work in a direction laterally to the forward feed comprising a laterally movable work centering element adapted revolvably to support the work piece, for rotary movement about an axis offset from the axis of the needle of the machine, a lateral feed transmission for feeding said centering element laterally including a rotatable member, a lever arranged normally to be rotated thereby; motion transmitting connections between said lever and the said work centering element, said connections including a second lever positioned to be engaged by and to respond to the movement of said first lever, and an operative connection between said second lever and said work centering element, and means for driving the stitch forming means and said lateral feed means in synchronism, the lateral feed of the work and the revolving thereof on the said work centering means in consequence of the stitching operation thereby causing the stitching means to produce a spiralling seam on the work.

4. The combination of claim 3 including adjustable means for effecting a temporary dwell in the response of said second lever to the movement of said first lever so that the lateral feed of the work is interrupted and a circular seam is caused to be produced during the period of dwell.

5. The combination of claim 3 including means

for delaying the response of said second lever to the action of said first lever so that the work is caused merely to revolve about said work center during the period of delay.

5 6. The combination of claim 3 including adjustable means for controlling the position of the work centering means relative to the stitching needle so that the spiral seam to be formed is caused to start a predetermined distance from the center about which the work is caused to revolve.

7. In combination with a sewing machine having stitch forming means including a needle, a presser foot, and feed means operative to feed the work in a forward direction, said presser foot and feed means being constructed for effective operation at one side only of the needle, means for imparting a bodily movement to the work in a direction transverse the direction of forward feed comprising a bodily movable work supporting element adapted to support a work piece for rotation about an axis offset from the axis of the needle of the machine, a feed transmission for actuating said element transverse the path of the forward feed from one limit of shift to another including a rotatable member, means for driving said rotatable member in synchronism with the operation of the stitch forming means of the machine, connections between said rotatable member and the said work support comprising a pivoted cam lever having a cam surface normally engaged by said rotatable member and connections between said cam lever and said work supporting element for actuating the latter, spring means operative on said cam lever and normally tending to move said cam lever in a direction counter to the action of said rotatable member, and relatively stationary abutment means positioned to be engaged by said cam lever for limiting the extent of the said counter movement thereof so as to maintain the cam surface of said cam lever spaced from said rotatable member during an initial portion of the movement of the latter.

45 8. A spiral seam producing mechanism for a sewing machine having a work table, stitch forming means including a needle, a presser foot, and feed means operative to feed the work in a forward direction, comprising a laterally movable work supporting pivot mounted above the work table and offset from the axis of the needle of the machine, a feed transmission for shifting said pivot in a direction transverse the path of forward feed including a rotatable member also mounted above the work table, means for driving said rotatable member in synchronism with the operation of the stitch forming means of the machine, a cam lever also mounted above the table operatively responsive to the movement of said rotatable member, power transmitting means between said lever and said work supporting pivot, operative to shift said pivot laterally in response to the movement of said rotatable member, and means for varying the rate of movement of the rotatable member relative to the rate of the stitching operation whereby to produce a seam in the form of a spiral with selectively controlled spacing of its convolutions.

9. In combination with a sewing machine having a work table, stitch forming means including a needle, a presser foot, and feed means operative to feed the work in a forward direction, a means for imparting movement to the work simultaneously in a direction laterally of the forward feed comprising a laterally movable work supporting

pivot mounted above the work table and laterally offset from the needle axis of the machine, a feed transmission for actuating said pivot laterally relative to the direction of forward feed, including a rotatable member mounted above the work table, means for driving said rotatable member in synchronism with the operation of the stitch forming means of the machine, a cam lever also mounted above the table operatively responsive to the movement of said rotatable member, motion transmitting connections be-

tween said lever and said work supporting pivot, and means for varying the speed of the said feed transmission relative to the rate of forward feed incident to the stitching operation whereby to produce a spiral seam with a predetermined spacing between the convolutions of the spiral.
